AUTOMATIC HEAT CONTROL FOR RADIATORS

Filed April 23, 1928

UNITED STATES PATENT OFFICE

WILLIS E. ROYS, OF BROOKLYN, NEW YORK

AUTOMATIC HEAT CONTROL FOR RADIATORS

Application filed April 23, 1928. Serial No. 272,013.

This invention relates to automatic heat controls for radiators.

The main object of this invention is the provision of an improved thermostatic heat 5 control for radiators.

A supplemental object of this invention is to provide a device of the character described, wherein improved means permits an automatic heat control of the nature specified to 10 be set to any temperature, regardless of whether the heat control is used in residences, apartment houses, private offices, and the like, where varying conditions may be required, or schools, or office or public buildings or hotels where a fixed temperature is observed.

Another object of the invention is to provide an improved device of the nature set forth which may assume the form of a knob that embodies the constructional adjustment 20 details herein involved.

A further object of the invention is the provision of an adjustment knob of the character set forth which may be made in different forms, including particularly a ratchet type 25 for use in dwellings, and the like, and a locking type for use in public buildings and similar places as above specified, the said knob being simple in construction, inexpensive of manufacture, and efficient, nevertheless, to a 30 high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a sectional side elevation of my improvement in the ratchet form, and showing 45 the application thereof.

Fig. 2 is a similar fragmentary view showing the locking type of knob.

Fig. 3 is a vertical section taken on the line 3—3 of Fig. 1.

Fig. 4 is a front elevation of an embodiment of the invention applied to a steam radiator. 50

Fig. 5 is an enlarged sectional view of a detail of invention.

Fig. 6 is an enlarged fragmentary view of 55 a detail of invention.

This invention constitutes an improvement on the automatic heat regulator for radiators more particularly shown and described in my Patent No. 1,522,981. 60

The advantages of the invention as here outlined are best realized when all of its features and instrumentalities are combined in one and the same structure, but, useful devices may be produced embodying less than 65 the whole.

It will be obvious to those skilled in the art to which the invention appertains, that the same may be incorporated in several different constructions. The accompanying drawing, therefore, is submitted merely as showing the preferred exemplification of the invention. 70

Referring in detail to the drawing, 10 denotes a device embodying the invention. The same includes a heat control 11, adapted to be mounted in the steam supply line 12 of a conventional radiator 14, in either top position (as shown) or at the bottom thereof according to the necessary conditions. 75

The control 11 may be described, generally, as including thermostats 15 and 15a which are horizontally aligned in position to actuate a valve 16 in the steam line 12. A cage 17 surrounds the thermostats and the auxiliary mechanism and insulating members. The said cage is secured to a flange 18 of the said valve, and is provided at its other end with a perforated plate 19, to which an adjusting 80

means 20 may be secured, for setting the heat control.

Taking around the stem of the valve 16, is a flexible bellows 21, having at one end a metal plate 22, faced with a strip of cork insulation 23. Secured in any suitable manner to the insulation 23, as by cement, or fasteners, is a disc 24. Coating therewith is a similar disc 25, and these are in parallel spaced relation with one another, being so retained by cork spacers 26, through which pass the fasteners 27. The discs 24, 25 are made of any suitable material to prevent radiation of heat from radiator 14 or valve 16 on the thermostats, so that the latter may more readily respond to changes in room temperature.

Improved means 28 is provided for interconnecting thermostats 15 and 15a, and also the latter with the insulating disc 25 to permit rapid assembling of the heat control. The said means includes the alined members 29 and 30, each of which is secured in any feasible manner to its coacting part of the heat control, as for example, by soldering exteriorly at 31. The said members have threaded engagement with one another at 32. Therefore, by a simple rotation, the thermostat 15a is secured to disc 25, and the thermostat 15 to 15a.

The adjusting means 20 comprises a stationary circular member 33 secured to the plate 19 in any suitable manner at 34. An inward extending flange 35 is grooved transversely to slidably receive the ridges 36 of the hub 37. The latter is fixedly secured to a side of the thermostat 15 in coaxial relation therewith and extends centrally into the body 33. Preferably, the said hub is threaded into the thermostat as shown at 38. At its other end, the said body is internally flanged at 39 and rabbeted at 40 to receive an annular shoulder 41 of a screw 42. This screw is threaded centrally into the hub 37 as shown at 43, and with respect to which it is rotatable. The said ridges are preferably three in number.

A knob 44 is externally mounted on the body 33, the latter being received within the cylindrical wall 45 of the former, which wall extends into proximity to the plate 19. A vertical wall portion 46 of the knob has a central opening 47 into which projects the adjacent end 48 of the adjusting screw 42. Communicating in alinement with the aforesaid opening is a hole 49 through which extends a screw 50, or other fastening, which is threaded into the portion 48.

Coacting with the knob 44 and the mounting 33, is a lock structure 51. The same includes a flat spring 52 seating in a recess 53 in the front face of the knob, which spring is clamped fixedly to the knob by the screw 50. A pin or detent 54 secured to an end of the spring extends inward through knob 44 in

parallelism with the axis thereof. The end of the detent is selectively received in one of a plurality of recesses 55 which are equally spaced from the said axis. A projection or point 56 on the knob 44 may indicate the position thereon for a given temperature.

The operation of the device will now be clearly apparent. On turning the knob 44, the pin 54 leaves its coacting recess and moves outward, the spring 52 being caused to deflect. On engaging another recess, the knob is again temporarily locked and may be permitted to so remain. The spacing between the recesses may be so determined as to afford a required or convenient difference in temperature in shifting from one to another. The thread on adjusting screw 42 is preferably of a quadruple character so that a slight turn of the knob 44 may cause a sufficient movement of the hub member 37, whether inward or outward, to set the thermostats 15 and 15a to operate valve 16 for permitting the required amount of steam to pass therethrough to radiator 14.

In Fig. 2 is shown a modification of the invention wherein the pin 54 is replaced by a screw 57 threaded through the end wall 58 of the knob 59. The end of the screw extends into a recess 60 in the flange 61 of the mounting body 62. The head of the screw 57 may seat in a depression 63 in the said end wall 58. A flat spring or plate 64 clamped in place in the recess 65 of the knob overlies and conceals the head of the screw 57.

It is thus seen that I have provided a device which fulfills the several objects of the invention and is well adapted to meet the conditions of practical use.

I claim:

1. A device of the character described, including a valve, a bodily movable thermostat to operate the valve, a casing for the thermostat, a stationary sleeve having inwardly offset portions directly engaging the casing to hold the sleeve in axial alinement with the thermostat, a knob mounted on the sleeve, a screw threaded device in axial alinement with the sleeve and movably guided by said offset portions, said screw threaded device having a member coacting with the offset portions to be retained thereby against rotation, said screw threaded device coacting with the thermostat and being actuated by the knob to set the thermostat for any desired temperature, said sleeve and said screw threaded device being positioned interiorly of the knob.

2. A device of the character described, including a valve, a bodily movable thermostat to operate the valve, a casing for the thermostat, a stationary sleeve alined with the thermostat, said sleeve having an edge portion offset toward the interior of the sleeve and forming an outer peripheral groove in the sleeve, said casing having an

opening to rigidly engage the sleeve in the groove, said portion having a plurality of opposite axially extending guide notches opening inward into the sleeve, a member centrally fixed to the thermostat and extending axially into the sleeve, said member having longitudinal guides slidingly engaging in the guide notches, an axial screw in the sleeve, said screw being fixed in the sleeve 5 against longitudinal movement and having loose threaded engagement with said member to move the latter axially, and a knob on the sleeve connected to the screw.

In testimony whereof I affix my signature.

WILLIS E. ROYS.
